(57) **CLAIM**

The ornamental design for a paper product with surface pattern, as shown and described.

DESCRIPTION

The sole FIGURE is a top view of a paper product with surface pattern, showing my new ornamental design. The paper product is shown broken away in both the horizontal and vertical directions. The broken away lines in the drawings indicate the appearance of any portion of the article between the break lines forms no part of the claimed design. The broken line boundaries surrounding the claimed design are understood to form no part of the claimed design. The thickness of the paper product forms no part of the claimed design.
